Atty.

UNITED STATES PATENT OFFICE

SAM BRISKIN, OF CHICAGO, ILLINOIS, ASSIGNOR TO EXCEL AUTO RADIATOR COMPANY,
OF CHICAGO, ILLINOIS, A CORPORATION OF DELAWARE

RADIATOR

Application filed October 3, 1928. Serial No. 310,072.

The present invention relates to radiators, such as those used in motor vehicles, and has reference more particularly to the structure of the radiator core.

5 Among the objects of the invention is to provide a novel radiator core with increased heat exchange characteristics and increased exposed surfaces for both the water and air contacts when the water is the medium to be cooled or changed in temperature and the air is the cooling medium, such as in an automobile radiator.

10 Another object is to provide such a core with increased length of travel of the water as also a more devious path whereby greater cooling can be effected in a given period of time and also whereby the passage of the water is subjected to cooling effects for a greater length of time.

15 A further object is to so pass the air into the air passages as to cause a greater spread of the air streams over an increased absorbing or heat transferring surface, by causing the air to be deflected, parted or otherwise made to take deviated or tortuous paths whereby the air more efficiently cools the walls of the water channels. This may be effected by a suitably formed or shaped spacer or interspacer between a pair of water channels, such that the contact between the spacer and the neighboring walls of the channels, shall be only in a few points or lines, thus eliminating contacts over extended surface areas as heretofore, and providing for a substantially total or complete exposure of the 20 surfaces of the channel walls to the cooling fluid, such as the air. Although mention is made of contacting of these parts in a few points, it is to be understood that the structure is such that the interspacer may not be in contact with the side walls of the water channels, but held in spaced relation between the same, the interspacer being held or supported at the ends or marginal portions, 25 where the marginal portions of the water

channel walls are secured or soldered to the marginal portions of the interspacer.

Other objects, advantages, capabilities and features are comprehended by the invention as will later appear and as are inherently possessed thereby.

50 Referring to the drawings:

Fig. 1 is a view in elevation of a part of a core constructed in accordance with the invention;

55 Fig. 2 is a top plan view of the same;

Fig. 3 is a transverse sectional view taken in a plane represented by line 3—3 in Fig. 2 of the drawings;

60 Fig. 4 is a horizontal sectional view taken in a plane represented by line 4—4 in Fig. 3 of the drawings;

65 Fig. 5 is a vertical sectional view taken in a plane represented by line 5—5 in Fig. 3 of the drawings; and

Fig. 6 is a side view of the insert, spacer or interspacer.

70 Referring now more in detail to the drawings, the embodiment selected to illustrate the invention is shown as comprising water channel walls 1 and 2 spaced from each other to provide a passage or channel 3 for the liquid to be cooled, such as water. Between the wall 1 of one channel and the wall 2 of another channel is a space 4 through which air or other cooling medium passes transversely for absorbing heat from the neighboring surfaces of the walls 2 and 3, and in this space is located a spacer or interspacer, all as clearly shown in Fig. 3 of the drawings.

75 The side walls 1 and 2 of a pair of water channels are made of strips of thin metal and are connected at the upper and lower ends by a lock seam 6 or the like, which may be suitably made fluid tight, as by soldering. The spacer 5 is also preferably made of thin metal and merely is inserted in the space 4 with the ends of the spacer in contact with the top and bottom walls 7 of the section or segment of the core.

90

Each water channel wall is formed with bent portions or corrugations so as to provide indentations or dihedral angles 8, which may be more or less acute and with intermediate or adjoining bent portions forming obtuse angle portions 9. By making each of the metal strips with these indentations, it will become apparent that the surface along the same will be greatly increased in area so that the water passing over such surface will have a longer path of travel as also having a deviated or tortuous path, thus tending to decrease the speed of flow of the water as well as increasing the length of time of passage of the water through the channel.

The interspacer 5 extends normally substantially through a medial plane in the space 4, and has medial body portions 10 and laterally indented or bent portions 11 and 12 extending in opposite directions from the medial plane in which the interspacer is located. These indentations 11 and 12 are located opposite the indentations 8 of the water channel walls and may contact with the same at a few points, or along a line of contact. In this way the sides of the indentations 8 are wholly out of contact with the sides or any other portion of the interspacer, thus giving increased exposed surface for cooling effect when the air passes between the interspacer and the channel side walls.

The indentations 11 and 12 are preferably tapered at the ends to form air deflecting portions 13 adjacent to the openings through which the air passes when passing through the passages 4. The deflecting portions 13 will act to slit or part the air stream and cause a portion of the air to pass on one side of the indentation and the other portion on the other side thus causing the air to spread over the neighboring surfaces of the adjacent channel wall on both sides of the indentation 11 or 12.

The marginal or edge portion of the channel walls and the interspacers are formed and shaped to be brought together into polygonal form, such as hexagons, shown in Fig. 1 of the drawings. The hexagons form openings at the ends of the passages 4 in which the interspacer is located. Referring to Fig. 1, it will be noted that the indentations in the interspacer and also in the channel walls are located substantially along the axes of the hexagonal openings, so that as air enters into these openings, it will first be deflected by the tapered surfaces 14 and is then caused to flow into two streams over the tapered portion 13 and on both sides of the indentations 11 or 12. Also it will be noted that the adjacent indentation 8 is also located to receive the air which passes over the inclined surface 15 and is then

parted to pass on both sides of the angle or indentation 8.

For the purpose of aiding the positioning of the different elements when assembling and ready for soldering the marginal portions, the sides of the hexagons may be provided with suitable projections 16 adapted to fit in suitable depressions 17 formed in the adjacent contacting surface of the hexagons. When so assembled, the marginal portions may then be dipped in molten solder and after cooling, these marginal portions are sealed together against leakage of fluid.

In operation, the water passes downwardly through the channels 3 and the air passes transversely through the hexagonal openings and into the passages 4, where the air streams are caused to spread over the entire surface of the channel walls as well as over the entire surfaces on both sides of the interspacer. It will be noted that the space between one of the dihedral angles 9 and adjacent portions of the angles 8, and the opposite portions of the interspacer, is substantially narrow, so that there is a greater chance of all of the air coming in contact with the outer channel surface or wall for increased cooling effect.

While I have herein described and upon the drawings shown an illustrative embodiment of the invention and its mode of use, it is to be understood that the invention comprehends other constructions, details, arrangements of parts, and features without departing from the spirit thereof.

Having thus disclosed the invention, I claim:

1. A radiator core comprising two walls connected at their ends and having relatively spaced apart areas provided with inwardly extended apiced ribs of angular cross section, and an imperforate sheet-like spacer interposed between said walls and having oppositely extended apiced ribs of similar angular cross section, the high portions of the spacer ribs engaging with the high portions of the wall ribs with a contact of minimum area, so that approximately the entire surfaces of the walls on both sides of the spacer are exposed to the air streams passing through the core, the marginal portions of said walls and said spacer having air inlet openings, the contacting portions of said ribs being located along the axes of said openings.

2. A radiator core comprising two walls connected at their ends and having relatively spaced apart areas provided with inwardly extended apiced ribs of angular cross section, an imperforate sheet-like spacer positioned to extend approximately through the medial plane in the space between said separated areas, the body of said spacer having oppositely extended laterally indented ribs

of approximately angular cross section, the high portions of the spacer ribs engaging with the high portions of the wall ribs so that substantially the entire surfaces of the
5 walls on both sides of the spacer are exposed to contact with the air streams passing through the radiator, said walls and said spacer having marginal portions forming air inlet openings, the contacting portions
10 of said ribs being located along the axes of said openings, said spacer having deflector portions adjacent said openings.

In witness whereof, I hereunto subscribe my name to this specification.

15 SAM BRISKIN.
